DRIVING MECHANISM

Eugene H. Haug, Chicago, Ill., assignor of one-third to Hugh E. Young and one-third to Eugene S. Taylor, both of Chicago, Ill.

Application May 23, 1932. Serial No. 613,075

1 Claim. (Cl. 74—21)

This invention relates to improvements in driving mechanism and, more especially, in combination with an endless flexible driving member carried between two wheels, pulleys or sprockets. The invention is especially applicable in connection with the so-called caterpillar drive in which the driving means includes an endless flexible driving member mounted as stated above, operating in connection with a driven member 5 parallel and adjacent to one of the reaches of the driving member.

In mechanism of the character referred to, the driving member is provided with lugs, dogs or jaws adapted to engage parts on the driven member. As the driving member passes over the supporting wheel at the end of the reach, the driving jaw, being radially mounted, increases its velocity. This would cause undue pressure against the part on the driven member, with consequent binding and unequal distribution of the load, unless means is provided for releasing the driving engagement before and as the jaw passes over the supporting wheel. One of the features 20 of my invention is the provision of driving mechanism to effect such release.

Other features and advantages of my invention will appear more fully as I proceed with my specification.

In that form of device embodying the features 30 of my invention shown in the accompanying drawings—

Figure 1 is a view in side elevation; Figs. 2, 3 and 4 are similar views showing, respectively, engagement and release of the driving jaw; Fig. 35 5 is an enlarged view in side elevation of a pair of driving jaws; Fig. 6 is a top plan view; Fig. 7 is a view taken as indicated by the line 7 of Fig. 6; Fig. 8 is a view taken as indicated by the line 8 of Fig. 7; and Fig. 9 is a view taken as 40 indicated by the line 9 of Fig. 8.

As shown in the drawings, for the purpose of illustrating the invention, the driving member is here shown as a flexible chain carried on the supporting sprockets 8 and 9 adapted to be driven 45 in the direction indicated by the arrows. The chain includes the long links 10, short links 10^a and a plurality of supports 11 here shown as also comprising links of the chain itself. Each of the supports 11 carries a pair of jaws 12 and 13 50 pivotally mounted in the support. This mounting is accomplished in the following manner. The support 11, as has been stated, forms one of the links of the chain. The side plates of this link are indicated by 11^a, 11^b. Each of the jaws 12 and 13 is provided with a pair of trunnions

mounted in suitable bearings in the side plates 11^a. The trunnions on the jaw 12 are indicated by 12^a and those on the jaw 13, by 13^a.

One trunnion on each jaw (on opposite sides of the chain) has a squared extension. These 60 squared extensions are indicated by 12^b and 13^b, respectively. Each of these squared extensions carries an operating lever. Such operating lever for the jaw 12 is indicated by 14 and the one carried by the jaw 13 is indicated by 15. Each of 65 these operating levers carries a roller, such rollers being indicated by 14^a and 15^a, respectively. These rollers are adapted to engage cams when the driving member moves to cause the jaws to release, as is hereinafter more specifically described.

The jaws are equipped with segments 12^c and 13^c, respectively, carrying intermeshing gear teeth 12^d and 13^d. By means of these gear teeth 75 movement of one jaw will move the other in a well-known manner.

16 indicates a cam surface adapted to be engaged by the roller 14^a on the arm 14. This cam surface has a curved end 16^a at its forward end and a similar curved surface 16^b at its rear end. 80 17 indicates a cam surface on the other side of the chain for engaging the roller 15^a on the arm 15. This cam surface similarly has a curved portion 17^a at the front end and a curved portion 17^b at its rear end. 85

Assuming that the chain is traveling in the direction indicated by the arrows, it will be seen that the jaws 12 of each part do all the driving, said jaws operating against pins 20 carried by the driven member, shown as a chain or conveyor 21. When operating in the direction indicated by the arrows, the jaws 13 of each part serve to prevent overrunning; and said jaws 13 will do the driving when the apparatus is 90 operated in the reverse direction. 95

Assuming that the apparatus is operating in the direction indicated by the arrows, it will be seen that the jaws 12 do all of the driving. It will be seen, also, that as the driving chain passes over the pulley 9, the horizontal speed 100 of the ends of the jaws 12, where they engage the pins 20 will be increased, due to the radial mounting of said jaws, unless some means is provided for releasing the driving engagement. If such release were not provided, there would be an undue strain on each jaw as it started to pass over the pulley 9 so that the jaws at such point would take too much load. The jaw 12 is pivoted in the supporting member 11 on the trunnions 12^a, as above described. This pivotal 105 110

mounting permits the jaw 12 to be moved from operative or driving position where it will engage the pin 20 to inoperative or release position where it will clear such pin. Such 5 rotational movement of the jaw from one position to the other is controlled by the arm 14 which is operated by contact of the roller 14^a on the arm with the cam surface 16 and the curved ends 16^a and 16^b thereof. When the apparatus 10 operates in the direction indicated by the arrows, the roller 14^a on the arm 14 engages the curved end 16^a of the cam track to bring the jaw 14 up into driving position where it will engage the adjacent pin 20. It is held in this driving position as the roller 14^a moves along on the horizontal track 16. Just before the jaw reaches the wheel 9, however, the roller 14^a runs down the curved end 16^b of the track 16, thus causing the jaw 12 to swing back away from the 20 pin 20 into its release or inoperative position. This release is fast enough so that after the jaw 12 once leaves the pin 20, it will not engage it again as it passes over the wheel 9, even though its facility is considerably increased, due 25 to its radial mounting. Any undue loading on the jaws 12 is thereby prevented where they pass over the wheel 9.

When the device is reversely operated, the 30 driving jaws 13 are similarly controlled by the wheels 15^a on the arms 15. The rollers 15^a engage the curved portions 17^b of the track 17 to bring the jaws 13 up into driving position and such jaws are released by the rollers 15^a running down the curved portion 17^a of the track 17.

75

In Fig. 2, the jaw 12 is shown in driving position. In Fig. 3, the roller 14^a has just commenced to descend the curved portion 16^b of the track 16 to release the jaw 12 from the pin 20 just before the jaws 12 reach the periphery of 80 the wheel 9. In Fig. 4, the jaw 12 has reached the wheel 9 and the roller 14^a has left the track 16^b so that the jaw 12 is released enough to 85 permit the jaws to pass over the wheel 9 without causing re-engagement with the pin 20.

90 While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as permissible, in view of the prior art.

95 What I regard as new, and desire to secure by Letters Patent, is:

In combination with a flexible driving member passing over a supporting wheel, an automatic gripper, including; a support mounted on 100 the driving member; a pair of jaws pivotally mounted in the support, said jaws being equipped with segments carrying intermeshing gear teeth; and an operating lever attached to one of said 105 jaws, said operating lever carrying a part adapted to engage a stationary cam surface by movement of the carrier to operate the jaws.
